UNITED STATES PATENT OFFICE.

JOSEPH H. CASPER, OF GREELEY, KANSAS.

REVERSIBLE RATCHET-WRENCH.

1,214,423.

Specification of Letters Patent. Patented Jan. 30, 1917.

Application filed May 19, 1915. Serial No. 29,121.

To all whom it may concern:

Be it known that I, JOSEPH H. CASPER, a citizen of the United States, residing at Greeley, in the county of Anderson and State of Kansas, have invented certain new and useful Improvements in Reversible Ratchet-Wrenches; and I do hereby declare the following to be a full, clear, and exact description of the invention, such as will 5 enable others skilled in the art to which it appertains to make and use the same.

This invention relates to new and useful improvements in reversible ratchet wrenches, and has for its principal object to provide 15 a wrench which is particularly adapted for use in removing gate valve seats.

Another object of the invention is to provide a wrench which may be readily reversed so as to easily and quickly remove 20 or replace the gate valve seats.

A further object of the invention is to provide a novel reversing means for the wrench.

Still another object of the invention is 25 to provide a novel means for holding the wrench in either of its positions so that it may be used as either a right or left hand wrench.

With these and other objects in view, the 30 invention consists in the novel combination and arrangement of parts which will be fully set forth in the following specification and accompanying drawings, in which,

Figure 1 is a side view in elevation of 35 a wrench constructed in accordance with this invention, Fig. 2 is a longitudinal sectional view on line 2—2 of Fig. 1, Fig. 3 is a longitudinal sectional view on line 3—3 of Fig. 2, Fig. 4 is an end elevation of 40 the main body of the wrench showing the latch and holding means therefor removed, Fig. 5 is a view in elevation of a fragment of a wrench, showing a modified form thereof, Fig. 6 is an end view of Fig. 5, Fig. 45 7 is a longitudinal sectional view through Fig. 5, and Fig. 8 is a fragmentary perspective view of the jaw member used in connection with the modified form of wrench.

Referring now to the drawings by characters of reference, the numeral 1 designates 50 as an entirety the main body portion of a wrench comprising the shank 2 which is formed with the enlargement 3. A central longitudinal aperture 4 extends through the shank and the enlargement and communicates with the chamber 5 which extends

transversely into the enlargement 3, being circular in plan and concentric therewith. A reduced opening 6 connects the chamber 5 with the countersink 7 in which the head 60 of the retaining screw seats when the same is in place.

The handle of the wrench is designated generally by the numeral 8 and comprises the cylindrical body 9 having formed there- 65 in the longitudinally extending central opening 10 which communicates with the opening 4 hereinbefore referred to. The opening 4 is provided with internal screw threads 11 at the upper end of the shank, and co- 70 operating with these screw threads is the reduced screw threaded extension 12, which extension forms a connection between the handle 8 and the shank 2. The end of the opening 10 opposite the inner end terminates in the depression 13 as clearly shown in Figs. 2 and 3. A pair of diametrically 75 opposite recesses 14 are formed axially in the depressed end 13 of the cylindrical body 9 as clearly shown in Figs. 3 and 4. 80

Extending longitudinally through the opening 10 is the stem 15 which is formed at its inner end with the enlargement 16, which in turn is formed with an aperture 16' for the reception of the pin 18 which 85 extends through a slot 17 in the ear 19 formed on the pawl 20. The end of the enlargement 16 opposite the one which joins the stem 15, is bifurcated to receive the ear 90 as clearly illustrated in Fig. 3. The pawl 20 is provided with the offset extension 21 provided with the cam face 22, the use of which will appear as the description proceeds. Secured to the end of the stem 15 opposite the enlargement 16 is the spherical 95 knob 21' which is formed with the opening 22' for the reception of the stem, and extending through the knob and through the stem is a pin 23 by means of which the knob 100 is held in place. A suitable pin 24 is threaded into the knob in such a position as to extend into either of the apertures 14 as clearly shown in Fig. 3.

Rotatably mounted in the chamber 5 of the enlargement 3 is a suitable cylindrical 105 body 25 which is formed with a plurality of outwardly extending peripheral teeth 26 at spaced intervals, which teeth are arranged to be engaged by the pawl 20 as clearly illustrated in Fig. 3. This disk 25 is formed integral with the disk 27 which is of greater 110 diameter than the disk 25 and is formed

with the diametrically opposite, peripheral notches 28, the walls of which are arranged to engage the gate valve seat in order to remove the same. A central opening 29 is formed in the body 25 and is arranged for the reception of the cylindrical portion 30 of the set screw, designated generally by the numeral 31, which is provided with the reduced screw threaded extension 32, which is threaded into the reduced, internally screw threaded opening 33 in the enlarged disk 27 hereinbefore referred to. A suitable enlarged, cylindrical portion 34 is formed at the end of the cylindrical portion 30 and is received in the opening 6 hereinbefore mentioned. The head 35 of the screw is received in the countersink 7, and it will thus be seen that the face of the wrench through which the screw extends, remains relatively smooth.

A suitable coil spring 36 surrounds the enlargement 16 and abuts the end of the reduced cylindrical portion 2 at one end and the shoulder, formed where the ear 19 joins the pawl 20, at the opposite end. It will thus be seen that the pawl will be forced downwardly so that the pin 18 engages the lower wall of the slot 17 and the member 21 engages the teeth 26 of the wheel 25.

It will be apparent from the foregoing that in use the spring 36 forces the pawl into engagement with the wheel 26, and when in the position illustrated in Fig. 3, it will be evident that the pawl will turn the wheel 25 clockwise. Upon pulling upwardly on the knob 21, it will be evident that the pin 24 will be withdrawn from engagement with the upper opening 14 and the whole may be reversed so that pin 24 will engage the lower opening 14, thus reversing the position of the pawl 20 so that upon oscillating the handle, the wheel 25 will be turned counter-clockwise. In the operation of this device it will be evident that the spring 36 performs a two-fold function, the first being the retaining of the pawl 20 in engagement with the ratchet wheel 25, and the second function being the holding of the pin 24 in engagement with the walls of either of the openings 14. It will thus be seen that the necessity of using a separate spring for holding the device in either of its adjusted positions is eliminated, and the same spring which is used to hold the pawl in engagement with the ratchet wheel, is used in holding the pawl in its adjusted position. It is further to be understood that if so desired, any suitable type of jaw may be substituted in place of the disk 27 by removing the screw 31 and placing a new jaw in position within the device.

In the modified form of wrench illustrated in Figs. 5 to 8 inclusive, the wrench body is formed identical with the construction illustrated in Figs. 1 to 4 inclusive but

in place of the wheel 25, there is substituted a ring 37 having formed in one end a plurality of screw threaded openings for the reception of the screws 38. These screws extend through openings formed in the flange 39, which flange is provided with the enlarged openings 40, the inner walls of which coincide with the inner wall of the ring 37. Formed integral with the ring 37 at the end opposite the flange 39 is a suitable flange 75 or enlarged portion 41 provided at diametrically opposite points with the recesses 42. The outer face of this enlarged portion is formed with screw threaded openings for the reception of the bolts 43, by means of which the auxiliary jaw member is secured in place. The periphery of the ring 37 is formed with a plurality of teeth similar to the teeth 26 formed on the wheel 25, and these teeth are arranged to be engaged by the pawl designated by the numeral 20 previously described. The construction of pawls and handles in this modified form is identical with the construction shown in the preferred form as clearly shown in Figs. 2 and 7.

The auxiliary jaw member best illustrated in Fig. 8 is designated generally by the numeral 44 and comprises the body 45, which is provided near each end with a pair of openings 46 and formed at each end of this body, is the upstanding portion 47 provided with the based extensions 48. These based extensions 48 form jaw members which engage the article to be turned. It is to be understood that a number of the jaw members 44 may be provided which vary in sizes so as to fit the larger as well as the smaller valves and by interchanging the jaw members, it will be clearly seen that the device may be universally used.

From the foregoing it will be apparent that the ring 37 may be rotated in the enlargement 3 in a manner similar to the wheel 25 and will also be held against rotation in one direction by means of the pawl 20. The jaw members 44 may be easily and quickly placed in position and removed on the enlargements 41, by merely the removal and replacing of the cap screws 43.

While in the foregoing there has been shown and described the preferred embodiment of this invention, it is to be understood that such changes may be made in the combination and arrangement of parts as will fall within the spirit and scope of the appended claims.

What is claimed is:

1. A ratchet wrench comprising a body, a handle on the body, a ratchet wheel rotatably mounted in the body, a pawl extending longitudinally through and slidably mounted in the handle and engaging the ratchet wheel, an operating stem slidably mounted in said handle, and means to lock said stem

against rotation, said pawl being slidably connected to said stem, whereby said pawl can move independently of said stem when engaged by said ratchet teeth on said ratchet wheel.

2. A ratchet wrench comprising a body, a handle on the body, a ratchet wheel rotatably mounted in the body, a pawl extending longitudinally through and slidably mounted in the handle and engaging the ratchet teeth on the ratchet wheel, an operating stem slidably mounted in said handle, means to lock said stem against rotation, said pawl being slidably connected to said stem, whereby said pawl can move independently of said stem when engaged by the teeth on said ratchet wheel, and spring means normally holding said pawl in engagement with said ratchet wheel and said stem in locked position.

3. A ratchet wrench comprising a body, a shank on the body, said shank being provided with a longitudinal bore, the body having a circular chamber formed therein and extending transversely thereof, said chamber communicating with the bore, a handle threaded on the shank, an operating stem slidable through the handle, a

knob at the outer end of the stem on the exterior of the handle, a lug on the knob, the stem being formed with a pair of diametrically opposite recesses for the reception of the lug, a pawl extending through the bore in the stem and into the chamber and slidably mounted therein, a cam face on the inner end of the pawl, a ratchet wheel rotatably mounted within the chamber co-operating with the pawl, an ear formed on the outer end of the pawl, said ear having a slot extending therethrough, said operating stem having its inner end bifurcated to receive said ear, a pin extending through the arm of the bifurcated portion of the stem and through said slot in the ear, whereby said pawl is slidably connected to said stem, and a spring normally holding said pawl in engagement with the ratchet wheel and the pin on said stem in engagement with the recesses in said handle.

In testimony whereof I affix my signature 50 in presence of two witnesses.

JOSEPH H. CASPER.
